UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

CORE DRILL.

Application filed May 5, 1924. Serial No. 710,963.

To all whom it may concern:

Be it known that I, HALBERT B. HALVORSEN, a citizen of the United States, residing at Michigan City, in the county of Laporte and State of Indiana, have invented certain new and useful Improvements in Core Drills, of which the following is a full, clear, and exact specification.

My invention relates to core drills.

10 An object of my invention is to provide an improved core lifter mechanism for such a drill. Still another object of my invention is to provide an improved core lifter mechanism having great strength and elasticity. 15 These and other objects and advantages of my invention will, however, hereinafter more fully appear.

In the accompanying drawings I have shown for purposes of illustration two 20 forms which my invention may assume in practice.

In these drawings,—

Fig. 1 is a central longitudinal sectional view of the lower end of a core barrel and 25 a drill bit in which my improved mechanism is embodied, the lifter section being on line 1—1 of Fig. 2.

Fig. 2 is a plan view of my improved core 30 lifter mechanism.

Fig. 3 is a side elevation of Fig. 2.

Fig. 4 is a plan view of a modified form 35 of construction.

In the illustrative form of my invention shown in Figs. 1 to 3, I have shown a hollow 40 core barrel 1 threadedly connected as at 2 to the upper end of a core lifter casing or shell 3, while the lower end thereof is threadedly connected as at 4 to a core drill bit 5, herein of the usual rotary diamond type. 45 The core lifter casing 3 is also as usual provided with an internal conical bore 6 in which a core lifter, generally designated 7, and of improved form, is disposed.

In my improved mechanism the core lifter 50 7 comprises a plurality of radially spaced wedge members 8 of identical construction which are provided with inclined surfaces 9 formed on their outer peripheries which engage the surface of the bore 6 formed in the casing 3. The lower inner ends of these wedges are provided with inwardly inclined surfaces 10, which direct the core upwardly through the core lifter. A radially expanding sheet metal core gripping spring member

11 is also rigidly connected to the inner peripheries 12 of the wedges by means of rivets 13, the latter being peened or headed over into counter-sunk bores 14 formed in the spring and the wedges. It will also be observed that the lower end of the radially expanding member 11 is spot welded as at 15, forming a smooth joint, while the upper end of the annular spring member 11 is provided with inwardly projecting fingers 16 inside each wedge. The radially expanding member 11 and one of the wedges 8 are also split as at 17, thereby permitting the ready expansion and contraction of the core lifter. In the form of my invention shown in Fig. 3, the spring 11' is provided with inwardly curved radially spaced surfaces 18 which are adapted to engage the core, the spring 11' being spot welded to the wedges 8' as at 19, thereby permitting a rigid construction to be obtained.

While I have in this application specifically described two forms which my invention may assume in practice, it will be understood that these forms of the same are shown for purposes of illustration and that the invention may be modified and embodied in other forms without departing from its spirit or the scope of the appended claims.

What I claim as new and desire to secure by Letters Patent is:

1. A core lifter comprising separate spaced wedge shaped supporting members, core gripping means provided with projecting core engaging members, and means for rigidly securing each of said supporting members to said core gripping means.

2. A core lifter comprising separate spaced wedge shaped supporting members, core gripping means having resilient projecting core engaging members, and means for rigidly securing each of said supporting members to said gripping means.

3. A core lifter comprising separate spaced wedge shaped supporting members, core gripping means having resilient projecting core engaging members, and means for rigidly securing each of said wedge members to the outer surface of said core gripping member.

4. A core lifter comprising separate spaced wedge shaped supporting members, resilient core gripping means connecting said members, said gripping means having inwardly

projecting core engaging members, and means for rigidly securing each of said wedge members to said resilient means.

5. A core lifter comprising separate spaced wedge shaped supporting members, spring core gripping means having auxiliary core engaging means formed thereon, and means for rigidly connecting each of said supporting members to said spring means.

10. 6. A core lifter comprising separate radially spaced wedge shaped supporting members, a radially expandible core gripping member having spring core engaging means carried thereby, and means for rigidly securing each of said supporting members to said expandible member.

7. A core lifter comprising separate spaced wedge shaped core supporting members, core gripping means having inwardly extending spring core engaging means carried thereby, and means for rigidly connecting each of said supporting members to said core gripping means.

8. A core lifter comprising separate spaced wedge shaped supporting members, a resilient annular split spring having core gripping elements formed thereon, and means for rigidly securing each of said supporting members to the inner surface of said spring.

9. A core lifter comprising separate spaced wedge shaped supporting members each having an inwardly inclined core guiding surface and a reduced portion, a split annular core gripping member disposed in said re-

duced portions adjacent said core guiding surfaces, and means for rigidly securing each supporting member to the outer surface of said core gripping member.

10. A core lifter comprising separate spaced wedge shaped supporting members each having a reduced inner surface and an inwardly projecting shoulder, a split annular core gripping member disposed adjacent said surface, the shoulders on said wedge members underlying the lower edge of said core gripping member, and means for rigidly securing each supporting member to the outer surface of said core gripping member.

11. A core lifter comprising separate spaced wedge shaped supporting members each having an inclined outer surface and a straight inner surface, a split annular spring member having core engaging means thereon, and means for securing said spring member to the inner surface of each of said wedge members.

12. A core lifter comprising separate spaced wedge shaped supporting members each having an inclined outer surface and a straight inner surface, a split annular spring member having inwardly projecting resilient core engaging fingers cut out therefrom, and means for rigidly securing said spring member to the inner surface of each of said supporting members.

In testimony whereof I affix my signature.

HALBERT B. HALVORSEN.
